UNITED STATES PATENT OFFICE.

ROBERT P. THRONE, OF SYRACUSE, NEW YORK.

MACHINE FOR MAKING CHAPLETS.

1,423,586.

Specification of Letters Patent. Patented July 25, 1922.

Application filed November 5, 1919. Serial No. 335,918.

To all whom it may concern:

Be it known that I, ROBERT P. THRONE, of Syracuse, in the county of Onondaga, in the State of New York, have invented new and useful Improvements in Machines for Making Chaplets, of which the following, taken in connection with the accompanying drawings, is a full, clear, and exact description.

This invention relates to certain improvements in the method of and apparatus for making molders' chaplets of the perforated sheet metal tubular type for positioning the core in the mold and for venting the gases therefrom during the introduction of the molten metal.

The main object of my invention is to successively perforate, feed, cut, and bend the chaplets into the desired form from a continuous strip of sheet metal in practically one and the same operation, whereby to greatly expedite the work, increase the output, and at the same time reduce the cost of production and labor incidental thereto.

Another object is to provide a simple, practical, and efficient mechanism which may be attached to any standard form of punch press for producing those results.

Other objects and uses relating to specific parts of the machine will be brought out in the following description:

In the drawings:

Figures 1 and 2 are similar sectional views of a portion of the machine embodying the features of my invention in which the sheet metal stock strip is advanced to the position to be perforated and formed, the punch and forming die being in its normal up position while in Figure 2 the die has assumed a position to sever the strip for a chaplet and to partially form the same while the perforating punches are about to enter the underlying portion of the strip for the next succeeding chaplet.

Figure 3 is a similar sectional view with the dies in position for completing the previously perforated and severed chaplet and for perforating the metal strip for the next succeeding chaplet, the main die being shown as attached to a portion of the plunger of a punch press while the metal strip is shown as coming from a reel.

Figure 4 is a perspective view of one of the completed chaplets.

The method of making these chaplets consists in feeding a continuous strip of metal endwise against a suitable stop, then sever-

ing a definite length of said strip from the stock and simultaneously bending it around a suitable form and at the same time perforating an adjacent portion of the same strip for the next succeeding chaplet, then withdrawing the perforating and forming means and removing the completed chaplet, and again feeding the strip against the stop ready for a repetition of the perforating and forming operation.

The apparatus illustrated for making these chaplets comprises a main supporting bed —1— upon which is mounted a hardened metal die —2— having a plurality of rows of vertical apertures —3— symmetrically arranged within a rectangular space within the margins of the die block —2— in uniformly spaced relation, the upper face of said die block being substantially flat and horizontal.

This die block is substantially rectangular and is firmly set or mounted in a recess —4— in the upper portion of the bed —1—, so that its upper inner corner may form a shearing edge to cooperate with a portion of the vertically moving plunger presently described, in shearing or severing a portion of the metal strip, as "A", which is to form the chaplet.

The metal strip "A" is fed from a reel "B" at one end of the base —1— and passes horizontally through a guide-way —5— in said base, said guide-way being of substantially the same width as the strip "A" and is registered with the upper surface of the die block —2— to enable the strip to be fed endwise across the surface of said block without excessive friction.

The base —1— is also formed with a vertical opening —6— just in front of the die block —2— and of sufficient length and width to easily receive the perforated and severed flat blank from which the chaplet is to be formed, the length of the blank being determined by a stop —7— which is secured to the upper face of the base —1— a distance from the inner face of the die block —2— corresponding to the length of the blank which may be necessary to form the chaplet.

A forming die —8— is mounted on the base —1— and extends transversely across the opening —6— in spaced relation to the end walls thereof, it being slightly nearer the inner end of the die block —2— than to the opposite end wall of said opening, corresponding approximately to the width of the forming die —8— in the direction and length

of the strip "A" to allow the forward end of the blank to be folded under the bar —8— and against the opposite end of the blank as shown in Figure 4.

5 The bar —8— is preferably rectangular in cross section, but of greater vertical height than its width lengthwise of the machine and determines the tubular form of the chaplet which is bent around the same 10 as will be hereinafter more fully explained.

A reciprocatory die or plunger —9— is movable horizontally and lengthwise of the machine along a suitable guide-way —10— in the base —1— for bending the advance 15 end of the blank under the lower face of the cross-bar —8—, the inner end of said plunger —9— being preferably rectangular in form has its upper face movable in a plane a slight distance below that of the 20 lower face of the bar —8— corresponding to the thickness of the metal of which the chaplet is formed.

An upper die-block —11— is suitably secured in a recess —12— of a supporting plate —13— which, in turn, is secured to a vertically reciprocating plunger —14—, whereby similar motion is imparted to the upper die-block —11.

A portion —8'— of the die —11— extends below the remaining portion thereof and is preferably rectangular in horizontal section and of substantially the same size as the opening —6— into which it is adapted to move, so that the lower corner at the 35 upper end face thereof may have shearing coaction with the adjacent inner end face of the die-block —2— for severing the previously perforated chaplet blank from the main body of the strip "A" as the plunger —9— descends from its normal position.

This die —14— is also provided with a substantially rectangular recess —15— opening from its lower face and registering with the cross-bar —8—, the width of said recess 45 being slightly greater than that of the cross-bar corresponding to the thickness of the metal at each side of said bar so that when the plunger is brought down the outer end wall of the recess which projects downwardly 50 slightly beyond the opposite end wall will first shear the blank from the main body and fold the corresponding end downwardly against the adjacent face of the bar —8— while the opposite wall will perform a similar function, in folding the corresponding 55 end of the blank downwardly across the adjacent face of said bar.

The distance between the adjacent faces of the die-block —2— and cross-bar —8— 60 is slightly greater than the vertical width of said bar, while the distance between the adjacent faces of the stop —7— and bar —8— is also greater than the vertical width of the cross-bar, whereby the ends of the 65 blank, when folded down across the opposite

sides of the bar —8—, will project beyond the lower edge thereof, at which time the plunger —9— is withdrawn outwardly, but immediately following the downward movement of the upper die —11—, said plunger 70 is moved inwardly to fold the adjacent end of the blank "a" across the under side of the bar —8— and into close proximity to the protruding opposite end of said blank, thus completing the tubular chaplet, as a'. 75

The means for effecting the reciprocatory movement of the plunger —9— consists of a bell crank lever —16— pivoted at —17— and having one arm engaged in an aperture —18— in said plunger, and its other end 80 connected by a retracting spring —19— to a suitable anchorage —20— on the vertically movable plate —13—. An adjustable stop-screw —20'— is mounted on the plate —13— and engaged with the upper edge of 85 the longer arm of the lever —16— for rocking said lever against the action of the retracting spring as the plunger —14— descends, thereby moving the plunger —9— inwardly to produce the final folding operation of the blank "a".

A punch die —2'— is mounted upon the block —11— to cooperate with the lower die —2— in perforating the interposed portion 95 of the sheet metal strip "A" and for this purpose is provided with a series of punches —2''— corresponding in number to the number of apertures —3— and registering therewith so as to readily enter the same for punching corresponding holes in the strip 100 "A" as the plunger —13— descends.

In order that the cutting resistance may not be excessive or too abrupt, the lower ends of some of the punches —2''— are arranged at different distances from the adjacent faces of the die —2— so as to enter the strip "A" one in advance of the other, and therefore the cutting resistance is considerably less than would be the case if all the punches entered the sheet metal at the 105 same time, thereby materially reducing the power required for the punching operation.

The punches of the male die and apertures of the female die are evenly distributed over a rectangular area slightly less than that of the sheet metal strip which is to form the blank and in such manner that the perforations will all be within the marginal edges of said blank, thereby leaving said edges substantially smooth and straight, 110 which enables the chaplets to be more accurately positioned in the machine.

The parts —2'— and —2— constitute what may be termed the male and female punch dies respectively, while the parts 115 —8— and —8'— may be termed the male and female forming dies, and the part —9— a supplemental forming die, the outer end face of the die —8'— being movable vertically across the inner end face of the die 120

—2— so that the lower outer corner as —21— may constitute a shearing edge co-operating with the upper inner corner of the die —2— to sever the previously perforated blank from the main body of the strip "A."

Mounted upon the base —1— directly above the punching die —2— is a guide-plate —22— forming with the main body of the base a lengthwise guide —23— and having a series of vertical guide openings —24— for the punches —2'— for the purpose of steadyng the punches as they are forced through the sheet metal strip "A" while the plate —22— serves to prevent upward displacement of the strip as the punches are withdrawn therefrom after the perforating operation.

Operation.

When the strip is first fed into the machine the die —13— is lowered to the position shown in Figure 2 which brings the outer end face of the die —8'— across the guide-way —23— to form a limiting stop against which the advance end of the strip abuts, whereupon the downward movement of the plunger is continued for the purpose of perforating the portion of the strip underlying the punches —2'—.

The plunger is then raised to the limit of its stroke as shown in Figure 1, whereupon the strip "A" is fed forward until its advance end engages the stop —7—, thus bringing the perforated portion of the strip directly over the forming die —8—. The plunger —13— is then brought downward to cause the die —8'— to fold the ends of the blank "a" upon the upper face and against the opposite upright sides of the die —8—, which brings the end of the blank nearest the supplementary —9— some distance below the lower face of the die —8— and into the path of said supplemental die which latter remains in its extreme outward position until the ends of the blank "a" have been folded against the opposite upright faces of die —8—, whereupon the lever —16— will be operated by the engagement of the adjustable screw —20— therewith to force the supplemental die —9— inwardly to fold the adjacent end of the blank "a" across the under side of the die —8—.

During this formation of the perforated blank around the die —8— the punching dies are brought into position to perforate the interposed portion of the strip "A" in the partial formation of another perforated blank.

The plunger —13— with the movable dies —2'— and —8'— thereon is then raised to the position shown in Figure 1, thus releasing the completed chaplet which has been formed on the die —8— and allowing it to be removed therefrom either by hand or by

any other suitable means not necessary to herein describe, except that it is to be understood that one end of the die —8— is unsupported to permit the removal of the completed chaplet therefrom by endwise sliding movement.

As soon as the die —13— is lifted to the position shown in Figure 1, the strip "A" may be again advanced against the stop —7— ready for the repetition of the operations previously described, these operations being continued in more or less rapid succession as long as the strip stock is available or until the required output has been reached.

What I claim is:

1. In a machine of the character described, the combination of a supporting bed having a female punching die, a forming-die and a horizontal longitudinally extending guide, all arranged in sequence along the bed, the female punching die being provided with a group of parallel vertical openings and a guide-way extending horizontally across said openings for receiving the work, a plunger movable vertically toward and from the supporting bed and provided with a male punching die and a forming-die arranged in sequence lengthwise of the bed, the male punching die having a group of punches vertically aligned with the openings in the female die and movable across the work guide as the plunger is lowered, said female punching die and the openings therein extending above the work guide to form guides for the punches, the supporting bed and plunger being provided with cooperating bearing members in a vertical plane between the punching dies and said forming-dies, a supplemental plunger slidable in the first named horizontal guide to and from a position beneath the forming-die on the bed and toward and from the female die, and means actuated by the first named plunger when moved toward the bed for moving the supplemental plunger toward the female die.

2. In a machine of the character described, the combination of a supporting bed having a female punching die, a forming-die and a horizontal longitudinally extending guide, all arranged in sequence along the bed, the female punching die being provided with a group of parallel vertical openings and a guide-way extending horizontally across said openings for receiving the work, a plunger movable vertically toward and from the supporting bed and provided with a male punching die and a forming-die arranged in sequence lengthwise of the bed, the male punching die having a group of punches vertically aligned with the openings in the female die and movable across the work guide as the plunger is lowered, said female punching die and the openings

therein extending above the work guide to form guides for the punches, the supporting bed and plunger being provided with cooperating shearing members in a vertical plane between the punching dies and said forming-dies, a supplemental plunger slideable in the first named horizontal guide to and from a position beneath the forming-die on the bed and toward and from the female die, and means actuated by the first named plunger when moved toward the bed for moving the supplemental plunger toward the female die, said means including a lever pivotally mounted on the supporting bed and an adjustable stop mounted on the first named plunger.

3. In a machine of the character described, the combination of a stationary support, a female die mounted on the support and provided with a group of parallel vertical openings and a work guide extending horizontally across said openings between the lower and upper ends thereof, a work stop on the support in alinement with the work guide and some distance in advance of the female punching die in the direction of feed of the work, a male forming-die mounted on the support between the female punching die and stop and having its upper face disposed in substantially the same horizontal plane as that of the work guide, a plunger movable vertically toward and from the support, a male punching die mounted on the plunger and provided with a group of punches in vertically alinement with the openings in the female punching die and movable in said openings across the work guide as the plunger is lowered for perforating the work in said guide, a female forming-die mounted on the plunger to cooperate with the male forming-die for folding the work thereon, a supplemental plunger slideable in a horizontal plane upon the support toward and from the female punching die and beneath the male forming-die for additionally folding the work upon the

last named die, and means actuated by the first named plunger when lowered for forcing the supplemental plunger toward the female punching die.

4. In a machine of the character described, the combination of a stationary support, a female die mounted on the support and provided with a group of parallel vertical openings and a work guide extending horizontally across said openings between the lower and upper ends thereof, a work stop on the support in alinement with the work guide and some distance in advance of the female punching die in the direction of feed of the work, a male forming-die mounted on the support between the female punching die and stop and having its upper face disposed in substantially the same horizontal plane as that of the work guide, a plunger movable vertically toward and from the support, a male punching die mounted on the plunger and provided with a group of punches in vertically alinement with the openings in the female punching die and movable in said openings across the work guide as the plunger is lowered for perforating the work in said guide, a female forming-die mounted on the plunger to cooperate with the male forming-die for folding the work thereon, a supplemental plunger slideable in a horizontal plane upon the support toward and from the female punching die and beneath the male forming-die for additionally folding the work upon the last named die, and means actuated by the first named plunger when lowered for forcing the supplemental plunger toward the female punching die, said means including a lever fulcrumed on the support and operatively connected to the first named plunger.

In witness whereof I have hereunto set my hand this 24th day of October, 1919.

ROBERT P. THRONE.
